[57] CLAIM

The ornamental design for a golf grip aid, as shown as described.

DESCRIPTION

FIG. 1 is a perspective view of a golf grip aid, showing my new design.

FIG. 2 is a top plan view thereof.

FIG. 3 is a bottom plan view thereof.

FIG. 4 is a side elevational view thereof.

FIG. 5 is a full cross-sectional side view thereof.

FIG. 6 is a perspective view of the golf grip aid, shown in configuration as worn around the finger.
